Primary Examiner—Stella Reid*Assistant Examiner*—Mark A. Goodwin(74) *Attorney, Agent, or Firm*—Caesar, Rivise, Bernstein, Cohen & Pokotilow, Ltd.(57) **CLAIM**

The ornamental design for a switchplate, as shown and described.

DESCRIPTION

FIG. 1 is a front view of a switchplate showing my new design.

FIG. 2 is an end view, with the opposite end being a mirror image thereof;

FIG. 3 is a side view, with the opposite side being a mirror image thereof;

FIG. 4 is a front view of a second embodiment of a switchplate showing my new design.

FIG. 5 is an end view, with the opposite end being a mirror image thereof;

FIG. 6 is a side view, with the opposite side being a mirror image thereof;

FIG. 7 is a front view of a third embodiment of a switchplate showing my new design.

FIG. 8 is an end view, with the opposite end being a mirror image thereof; and,

FIG. 9 is a side view, with the opposite side being a mirror image thereof.

The broken lines shown in FIGS. 1-9 are for illustrative purposes only and form no part of the claimed design.
